UNITED STATES PATENT OFFICE.

HAROLD DAVID THOMAS, OF NEW YORK, N. Y., ASSIGNOR TO AUTOMATIC SHOE SHINER CORPORATION, OF NEW YORK, N. Y., A CORPORATION OF NEW YORK.

DESIGN FOR A CASING FOR SHOE-SHINING MACHINE.

Application filed December 10, 1923. Serial No. 7,984. Term of patent 3½ years.

To all whom it may concern:

Be it known that I, HAROLD DAVID THOMAS, a citizen of the United States, residing at New York, in the county and State of New York, have invented a new, original, and ornamental Design for a Casing for Shoe-Shining Machine, of which the following is a specification, reference being had to the

accompanying drawing forming part hereof.

Fig. 1 is a front elevation.

Fig. 2 is a side elevation.

I claim:

The ornamental design for a casing for shoe shining machine, as shown.

HAROLD DAVID THOMAS.
